CLAIM

The ornamental design for a spotlight, as shown and described.

DESCRIPTION

FIG. 1 is a front perspective view of a spotlight according to invention:

FIG. 2 is a front elevational view thereof;

FIG. 3 is a side elevational view thereof; the opposing side being a mirror image,

FIG. 4 is a rear elevational view thereof;

FIG. 5 is a top plan view thereof; and,

FIG. 6 is a bottom plan view thereof.

The broken line showing of a square element in FIGS. 2, 3, 4 and 6 is for illustrative purposes only and forms no part of the claimed design.

1 Claim, 3 Drawing Sheets

FIG. 1

FIG. 5FIG. 6
